UNITED STATES PATENT OFFICE.

CHARLES E. MONFORT, OF UTICA, MICHIGAN.

WATCH-PIVOT.

SPECIFICATION forming part of Letters Patent No. 410,173, dated September 3, 1889.

Application filed January 3, 1888. Serial No. 259,592. (No model.)

To all whom it may concern:

Be it known that I, CHARLES E. MONFORT, a citizen of the United States, residing at Utica, county of Macomb, State of Michigan, have 5 invented a certain new and useful Improvement in Pivots for Watches; and I declare the following to be a full, clear, and exact description of the invention, such as will enable others skilled in the art to which it appertains to 10 make and use the same, reference being had to the accompanying drawings, which form a part of this specification.

My invention consists of the improvement herein described, and more particularly 15 pointed out in the claims.

In the drawings, Figure 1 represents an enlarged view of the balance-wheel staff of a watch. Fig. 2 represents the same in longitudinal section. Fig. 3 represents a variation 20 in which the removable pivot screws onto the shaft instead of into the shaft.

It is well known among watch-makers that one of the most difficult operations to properly perform is the introduction of a new 25 pivot when the original has been broken. It has usually required the watch-maker to draw the temper from the steel shaft or staff to soften it; then it has been necessary to drill the end of the shaft and to introduce therein 30 a new pivot which either before or after introduction has been properly turned and dressed.

It is the purpose of my invention to facilitate the renewal of a broken or deranged pivot of this character. To this end I make the 35 staff or shaft with an orifice in each of its ends, the said orifices being screw-tapped. I then provide the shaft with pivots, which are screw-cut to enter the said screw-tapped orifice.

40 In the drawings, A represents the balance-staff of a watch. B represents its pivots. These pivots are screw-cut at b to engage threads at b' on the shaft. I would have it understood that this pivot may be screw-cut 45 to enter a tapped orifice on the shaft, or it may be in the form of a screw-tapped cup, as shown in Fig. 3, to screw upon the end of the shaft. So, also, it may or may not be provided with an angular head b^2 to facilitate 50 grasping the same with a wrench or with pliers.

I do not limit myself wholly to the use of

this invention in watches; but it is applicable in clocks and in other localities where fine journal-pivots are apt to become broken.

55

It is well known to watch-makers that unless a pivot is perfectly true the whole operation of the watch is impaired, and should one become bent, broken, or distorted this invention enables an ordinary workman to 60 remove the broken or injured pivot and to replace it with one which is perfectly true, which leaves the watch in this respect as good as new, and enables the work to be done by an ordinary hand instead of requiring, as is 65 frequently the case, that the watch be sent at large expense to a factory or to some competent workman. It also obviates the necessity of heating the shaft to draw the temper, and thereby obviates warping, which frequently 70 results from this process.

I am aware of the device patented to Simon, October 24, 1871, No. 120,335. Simon's device, however, is simply a means for repairing a broken pivot by first turning a tenon on the 75 end of the broken shaft and then slipping thereon a separate pivot-cap. It is manifest, however, that the broken shaft must first be heated to draw its temper before the tenon can be turned on it, and this heating is apt to 80 ruin the shaft or stem. So, also, the cap being simply slipped on the tenon is very apt to fit more or less loosely, and the slightest play would of course impair the operation of the watch mechanism. My device, however, is not designed as a means for repairing 85 the broken pivots of ordinary stems; but I propose constructing the stem in the first instance with the said removable pivots and engaging the pivots with the stems by screw-threaded connections, so that the fit may be 90 perfect, and so that there may be absolutely no play between the parts. So, again, should it be desirable that the new stem should be slightly longer than the old one, to compensate 95 for wear at the pivot or for any other reason the screw-threaded connection forms a means for producing any desired adjustment of the length. So, also, should the end of either pivot become worn the screw-threaded engagement of the pivots affords means whereby both pivots may be slightly, so as to compensate for the wear without disturbing the 100 position of the other elements on the shaft.

with respect to the operative parts of the mechanism with which they are engaged.

What I claim is—

1. The combination, with the screw-threaded balance-staff A, of the pivots B, screw-threaded for engagement with the said staff, and having angular heads b^2 , substantially as described.

2. The combination, with the staff A, having an orifice, of the pivots B, said staff and pivots being screw-threaded for engagement with each other and together forming a length-

wise-adjustable balance-staff, substantially as described.

3. An extensible balance-staff consisting of 15 a shaft provided at one or both of its ends with a pivot engaged therewith by a screw-thread, substantially as described.

In testimony whereof I sign this specification in the presence of two witnesses.

CHARLES E. MONFORT.
